UNITED STATES PATENT OFFICE.

LOUIS L. MARTIN, OF TORONTO, ONTARIO, CANADA.

DOME-FASTENER MACHINE.

1,323,482.

Specification of Letters Patent.

Patented Dec. 2, 1919.

Application filed December 16, 1918. Serial No. 267,006.

To all whom it may concern:

Be it known that I, LOUIS LINNEAUS MARTIN, a subject of the King of Great Britain, and resident of the city of Toronto, county 5 of York, Province of Ontario, in the Dominion of Canada, have invented certain new and useful Improvements in Dome-Fastener Machines, as described in the following specification and illustrated in the accompanying drawings, that form part of the 10 same.

The principal objects of this invention are, to devise an automatically operating machine to perform the various operations 15 requisite to produce a dome fastener in which the operations follow successively in the passage of a ribbon of metal through the machine.

A further object is to devise a machine of 20 very compact form which will operate with great rapidity and accuracy.

The principal features of the invention consist in the novel construction and arrangement of parts, whereby a ribbon of 25 metal is fed through a succession of dies and the metal is drawn into the shape of a dome head and formed with a narrow neck portion by a spinning member which is operated in unison with the operation of the 30 various punches to grip and reduce the metal of the neck portion of the fastener at the proper period and whereby the metal is cleared from the dies by a positive action effected through the movement of the punches, 35 the whole being accomplished in the manner hereinafter described in detail.

In the drawings, Figure 1 is a front elevational view of a press equipped with my improved apparatus.

Fig. 2 is a side elevational view of a press 40 illustrated in Fig. 1 and showing the operating mechanism for the spinning device and the arrangement of the sub-press upon the larger press.

Fig. 3 is an enlarged end elevational view 45 of the sub-press and its operating mechanism.

Fig. 4 is a longitudinal sectional view 50 through the center of the forming dies.

Fig. 5 is a cross sectional view through 55 the sub-press showing the mechanism for operating the spinner tool.

Fig. 6 is an enlarged side elevational view 60 of the device for feeding the metal strip.

Fig. 7 is a sectional view through Fig. 6 55 on the line *a—b*.

Fig. 8 is a detail of the clutch of the feed mechanism.

The device constituting the present invention is herein shown applied to a punch 60 press having a base 1 supported upon the legs 2 and a frame 3 rising from the base and supporting the ram 4 and its operating shaft and pulley 5.

The machine proper for forming the article to be pressed is in the form of a sub-press 6 which is mounted upon the table of the base 1.

A spinning device is arranged upon a frame 7 supported below the base 1 from the 70 legs 2 and upon the frame 7 axially below the ram 4 is arranged a frame 8 supporting a vertical spindle 9 and upon this spindle is mounted a grooved pulley 10.

A grooved pulley 11 is mounted upon a 75 bracket 12 at the rear of the frame 7 and is arranged in horizontal alignment with the pulley 10 and a belt 13 connects said pulleys. The shaft 14 of the pulley 11 extends upwardly through a bearing 15 and at its upper end is provided with a universal joint 16 which connects with a shaft 17.

A friction pulley 18 is mounted on the 80 upper end of the shaft 17 and is adapted to engage the outer face of the main pulley 5 of the press to convey the rotating motion to the vertical spindle 9.

A collar 19 encircles the upper end of the 85 shaft 17 and this shaft is connected by the cap screw 20 with a bar 21 slidably arranged upon the frame 3.

A lock wheel 22 is arranged at the forward 90 end of the bar 21 having a pin 23 adapted to engage the notched end of the bar to hold it securely in the position with 95 the pulley 18 clear of the pulley 5.

A coil spring 24 is secured at one end to the cap screw 20 and at the other end to the fixed screw 25 and this spring has the tendency of drawing the pulley 18 into contact 100 with the main pulley 5.

A handle 26 is arranged on the side of the bar 21 for operating it.

A clutch member 27 of an ordinary type is arranged upon the press and is controlled 105 by the handle 28.

A stop member in the form of a projecting arm 29 is secured upon the bar 21 and

prevents the operation of the clutch until the bar 21 has been released to move to its forward position to effect the operation of the spindle 9.

- 5 The sub-press 6 is shown as a unit in Figs. 3 and 4 and comprises a base 30 which is secured to the base 1 of the main press and is formed with an upright frame 31 supporting a ram head 32.
- 10 33 is a die block secured upon the base 30 and formed with a row of counterbored circular orifices 34 and in these orifices are arranged the dies 35, 36, 37, 38 and 39. A circular space 40 is arranged between 15 the dies 38 and 39 for a purpose which will hereinafter appear. A circular die block 41 is arranged in a recess 42 in the block 33 having its surface in line with the surface of the dies 35 to 39.
- 20 The details of this die block will be herein-after described. A plate 43 rests upon the top of the die block 33 and is formed with a longitudinal recess 44 in the underside. A pair of stripper plates 45 are secured to the underside of the plate 43 and extend inwardly beyond the side walls of the recess 44. The metal strip A from which the dome fasteners are made is of a width corresponding to the 25 width of the recess 44 and is adapted to slide therethrough.
- 25 The dies are of a progressive nature adapted to draw the metal of the strip into a teat and suitable punches 46, 47 and 48 are secured in the block 49 secured to the ram 50 slidably arranged in the ram head 32. These punches draw the metal of the metal strip down into the dies and the drawing action is arranged progressively.
- 30 40 The plate 43 is formed with the upwardly projecting lug members 51 in which the arms 52 are pivotally mounted and said arms extend horizontally forward and are pivotally mounted in the rigid lugs 53 secured to the die block 33.
- 35 45 54 are cam plates pivotally mounted on the pivot pins in the lugs 53 and are formed with the lower portion thereof cut away so that the shoe portions 55 rest upon the 50 upper surface of the arms 52. The inward part of the shoe portion is curved upwardly to roll upon the surface of the arm as the cam plate is swung inwardly on its pivot but the heel portion 56 engages the 55 arm so that upon the cam plate being swung outwardly on its pivot the arm will be tilted in its bearing in the lugs 53 thereby lifting the plate 43 and the stripper plates 45 to engage the metal strip being formed and lift it 60 clear of the dies so that it may be fed forward through the die block the requisite distance for the next operation.
- 55 The cam plates 54 extend upwardly past the ends of the punch block 49 and the inner 65 faces are formed with cam grooves 57 which

extend in a downward sweeping curve from the inner edges to a horizontal opening.

58 are pins secured in the ends of the punch block and operating in the cam grooves 57.

70 As the block moves downwardly the pins engaging the inward face of the cam grooves tilt the cam plates on their pivots and when the pins reach the bottom of the grooves the coil springs 59 swing outwardly, thus 75 bringing the upwardly curved portions 60 of the cam grooves immediately over the pins.

80 As the punch block moves upwardly the pins 58 engage the cam surfaces 60 and tilt 85 the cam plates outwardly so that the heel portions 56 engaging the arms 52 lift the stripper plate.

85 In the center of the length of the plate 43 and at the side adjacent to the frame 81 of the sub-press is arranged a hardened steel anvil 61 and a lever 62 pivotally supported in the lugs 63 is held in spring contact with said anvil by the spiral spring 64 to hold the plate 43 down against the die plate. 90 The pressure of this lever is exerted upon one side of the stripper plate and in order to balance the said plate and keep it in a horizontal position a pair of lever arms 65 are arranged one at each end and pivotally 95 supported in lugs 66 and extend across the stripper plate each having a downwardly turned end 67 engaging the plate on the side opposite to the anvil 61.

100 Spiral springs 68 are connected to the 1 opposite ends of these levers 65 to exert a downward pressure against the plate.

105 The center lever 62 performs a double function in that it bears upon the anvil 61 and extends inwardly over the center of 1 the plate 43, the inner end 69 thereof being rounded.

110 A cylindrical block 70 is slidably arranged in the supplementary block 71 secured to the plate 43 centrally and this cylindrical 1 block is provided with a transverse slot 72 near its upper end into which the rounded end 69 of the lever 62 extends. The bottom end of the cylindrical block 70 bears upon the metal strip A while the neck of the 1 dome is being formed by the spinning apparatus which has not yet been described.

115 A pair of cylindrical blocks 73 and 74 are mounted on either side of the central block 70 in the supplementary block 71 and 1 are held downwardly in contact with the metal strip A by means of levers corresponding exactly with the lever 62.

120 The dies 35, 36 and 37 are forming dies and the dies 38 and 39 are practically positioning dies but the blocks 73 and 74 perform the function of tools for eliminating any inequalities in the surface of the metal strip caused through the drawing operations.

In order to accomplish the spinning of the neck of the dome a holder 75 is secured to the underside of the base of the sub-press and said holder is formed with a central 5 counter bore 76 and a central bearing 77 extends vertically downward therethrough. A spindle 78 is journaled in the bearing 77 and its lower end extends beyond the holder 75 and is provided with a collar 79 each side 10 of which are arranged thrust bearing collars 80.

The lower end of the holder 75 is threaded on the outer side and a cap 81 is secured thereto, said cap inclosing the thrust 15 collars and the collar 79 of the spindle.

The lower end of the spindle 78 is provided with a head 82 having a transverse pin 83 projecting each side thereof. This pin is engaged by a sleeve 84 secured to and rotating 20 with the upper end of the vertical spindle 9 and spring held in contact with the spindle 78 and pin 83. The upper end of the spindle 78 extending within the counter bore 76 is formed with an enlarged head 25 portion 85 and upon the top of this head portion is formed a ball-shaped member 86. A pair of jaw members 87 of semi-circular form in cross section are formed with a ball-shaped socket at the lower end to fit the ball 30 end 86 of the spindle and they are loosely held upon said ball end by a transverse pin 88 extending through the ball. The upper ends of the jaw members 87 are formed with recesses 89 and the upward extremities are 35 formed with inturned flanges which are adapted to engage the depressed seat in the metal strip A and to press it inwardly to form the neck of the fastener. The jaws when in contact with the metal are spun to 40 swage the metal inwardly. The jaws are normally held apart by means of a spiral spring 91 arranged in sockets in their inner faces above the ball.

A collet 92 encircles the upper end of the 45 spindle 78 and the upper edge thereof engages the beveled outer surfaces 93 of the jaw members 87 and when the collet is moved upwardly it forces the jaws inwardly into contact with the metal seat to effect the 50 inward swaging of the metal.

The lower end of the collet is encircled by a pair of thrust bearing washers 94 between which is arranged a collar 95 said collar having laterally extending pins 96 which project outwardly through the vertical slots 97 arranged in the upper end of the holder 75.

98 is a jaw-shaped member pivotally supported upon a pin 99 extending transversely through the holder 75, the jaw ends of said 60 member having the slots 100 engaging the pins 96 of the collet operating collar 95.

The outwardly extending end 101 of the jaw member 98 is provided with a pivotal block 102 arranged upon its upper side, said 65 pivotal block supporting a horizontally

journalized roller 103. The block 102 is set in adjusted positions by means of a set screw 104 threaded in the end 101.

A block 105 is secured to the edge of the base 80 of the sub-press in central alinement 70 with the holder 75, said block having a horizontal slide-way 106 in which is arranged a block 107 having a beveled under surface adapted to engage the roller 103 of the pivotal jaw member 98 to tilt said jaw 75 upon its pivot raising the collet and throwing the swaging jaws inwardly into contact with the side walls of the seat in the metal strip A.

The block 105 is formed with a vertical 80 slot 108 and in this slot is arranged a reciprocating member 109 formed with a beveled lower end 110. The outer side of the member 109 engages a roller 111 secured in the block 105 and the beveled side engages a 85 roller 112 journaled in the slide block 107 so that on the downward movement of the member 109 the block 107 is forced inwardly to operate the jaw member 98.

The ram 50 of the sub-press reciprocates 90 within the ram head 32 and said head is provided with a vertical slot 113 in the outer side through which a pin 114 secured to the ram extends.

A bar member 115 is pivotally secured to 95 the upper end of the reciprocating member 109 being adapted to swing freely in one direction transversely of the machine and being held in vertical alinement with the reciprocating member 109 by means of a spiral 100 spring 116 having one end secured to the member 109 and the other end secured to the bar 115.

The upper end of the bar 115 is flat and 105 is engaged by the pin 114 in the ram.

A double beveled projection 117 is formed on one side of the bar 115 and a bracket member 118 having a roller 119 is adjustably supported upon a plate 120 which is adapted to engage the beveled projection 110 of the bar 115 to cause said bar to swing on its pivot and disengage from the pin 114 of the ram at a predetermined point.

The bracket 118 is held securely in an 115 adjusted position but is adjusted by means of a vernier adjusting screw 121.

The ram of the sub-press is connected to the main ram 4 by a suitable dove-tail connection and is operated directly thereby.

As the ram 50 moves downwardly the pin 120 114 pressing upon the bar 115 moves the reciprocating member 109 downwardly in its slot and said member operating against the roller of the block 107 moves said block

125 into operating engagement with the roller of the jaw member operating the collet for closing the spinning jaws. When this operation has been effected and the spinning is completed the under beveled portion of the projection 117 engages the roller 119 on the 130

- bracket 118 and the bar 115 swings outwardly on its pivot and moves clear of the pin 114 and the ram continues its downward movement. The member 109 is immediately 5 returned to its normal position by the upward pull of the spiral spring 120' and the jaw member 98 and the collet operated thereby is returned to its lower position by means of the springs 123.
- 10 The die block 41 is formed to coöperate with the punches 124, 125 and 126, the punch 124 perforating the stitching holes. The punch 125 forms an annular rib around the central dome and the punch 126 cuts the finished article from the strip.
- 15 The ram operates with a regular reciprocating action carrying the punch block and punches and in each reciprocation each punch performs its particular operation.
- 20 The punch coöoperating with the die 35 makes the first impression in the metal. The next punch and die draws the metal farther and a still further drawing action is effected in the third punch and die forming 25 a prominently projecting straight-walled teat. In the fourth die the teat enters the recess therein and the block 73 is brought into engagement with the upper surface of the metal strip by the action of 30 the spring lever 62, said block forming a floating punch.
- A short punch 127 is adapted to engage the block 73 just at the period when the other punches have completed their stroke 35 so that any inequalities in the surface of the metal around the teat caused by the drawing of the metal will be effaced.
- The central block 70 is held in contact with the metal strip by the central lever 62 40 while the spinning of the neck occurs and the block 74 is spring held against the strip A to hold it in the die 39 which is merely a locating die. The next punch perforates the thread holes in the metal as described 45 and following this the punch 125 forms the annular rib and the completed blank is cut out by the die 126 and falls through an opening 128 into a chute 129 which delivers the finished article from the machine.
- 50 The various operations occur simultaneously and on each upstroke of the punches the metal strip is lifted clear of the dies by the stripper plate operating in the manner described and simultaneously the metal strip is fed through the die block the required distance. In the upward movement 55 of the stripper plate the anvil 61 engages the lever 62 and the corresponding levers operating the blocks 73 and 74, at a point on the inward side of their pivot and tilting 60 said levers on their pivots so that the inner ends lift upwardly with a movement faster than the movement of the plate thereby lifting the blocks or floating punches 65 clear of the metal strip A.

Inversely the downward movement of the floating punches or blocks is accomplished with a rapid movement in advance of the movement of the main punches so that the metal strip will be held in positive relation to the spinning die.

The feeding of the metal strip A is effected by the operation of a pair of feed rolls 130 and 131 which carry intermeshing gears 130' and 131'. These rolls are mounted in a frame 132 secured upon the base of the sub-press, the journals for the low roller being held stationary in said frame and the journals for the upper roller being formed in the blocks 133 and 134 which are slidably supported in the frame.

A plate 135 is arranged above the blocks 133 and 134 and roller bearings 136 are arranged on the under side thereof.

A compression spring 137 is mounted on the top of the plate 135 and an adjusting screw 138 threaded on the top of the frame adjusts the pressure of the spring.

The lower feed roll is preferably formed with a concaved periphery and the upper roll 131 is correspondingly convexed so that the ribbon or strip of thin sheet metal which is fed between the rolls is bent transversely, thus stiffening the metal against the distorting effect caused by the action of the dies.

The block 134 is provided with a cylindrical extension 139 which is recessed in the outer side to form a clutch surface and clutch disk 140 is rotatably mounted on the outer end of the spindle 141 of the upper roller.

A clutch member 142 is arranged with the disk 140 and is keyed to the spindle 141 and a similar clutch member 143 is also keyed to the spindle and arranged with the cylindrical extension 139.

Ball clutches 144 and 145 are arranged between the clutch members and their respective disks to operate in the manner hereinafter described.

An arm 146 is pivotally mounted intermediate of its length upon the frame 132 and one end thereof is connected to the clutch disk 140 by a connecting rod 147. The punch block 49 is provided with a roller 148 which is adapted to engage the opposite end of the arm 146 to swing said arm on its pivot as the punches move upwardly.

A coil tension spring 149 is connected to the arm 146 to draw it downwardly as the punch block moves down.

In the operation of the feed apparatus as the punch block moves upwardly the roller 148 tilts the arm 146 pushing downwardly on the connecting rod 147 and turning the clutch disk 140. As the clutch disk turns it binds upon the ball clutch member 144 and rotates the clutch member 142 thereby

turning the feed roller spindle the required distance to feed the metal strip A forward, this operation being timed to synchronize with the lifting of the stripper plate. The 5 secondary clutch holds the spindle from turning backward as the operation of the arm 146 reverses. The movement of the clutch 142 and consequently the movement of the feed rolls is regulated by means of an 10 adjusting screw 150 mounted on a bracket 151 on the top of the frame, said adjusting screw limiting the upward swing of the arm.

In the operation of this machine, the metal 15 from which the fasteners are made is carried upon a suitable reel and passing through the feed rolls is bent into concaved form. The strip extends into the longitudinal orifice in the plate 43 passing over the tops of the dies.

20 In the first downward movement of the press the metal is drawn into the first die in the manner shown and described. As the ram rises the plate 43 is lifted by means of the cam plates 54 to lift the drawn part of 25 the metal clear of the surface of the dies. While the stripper plate is thus raised the continuing upward movement of the ram operates the feed mechanism in the manner described to move the metal strip forward 30 the required distance so that the depression in the strip is brought into alinement with the depression in the second die. As the second operation is performed the first operation commences in the second position on 35 the strip. This operation is repeated until the portion of the strip having the downwardly formed teat comes opposite the central opening where the spinning die is located and as the punch moves downwardly 40 the reciprocating member 109 operates the mechanism described to close the spinning die jaws in upon the metal to form the neck of the fastener. When this spinning has been accomplished the collet is released from 45 the spinning jaws by the operation of the bar 115 and the operating parts are returned to normal. The dies arranged each side of the spinning die are principally for the purpose of properly locating the teat being operated upon by the spinner but the anvil punches serve to rectify any slight inaccuracies in the metal.

50 As the metal strip is further advanced the perforating punch operates to cut the sewing holes through the metal and the next succeeding die and punch stamp the metal surrounding the head into a raised annular rib and shoulder and incidentally true up the metal and hardening and dishing the metal 55 fastener to impart strength and rigidity thereto. The final operation punches the finished article from the strip. The spinning die spindle 9 operates continuously while the machine is in operation but when the 60 machine is stopped the spinning mechanism is

disconnected by the sliding bar 21 upon its supports.

The clutch mechanism is locked by means of the extension arm 29 so that the spinning mechanism must be put into operation before the press is started into motion. 70

It will be seen that the sub-press is a very compact unit and may be fitted to practically any type of press and being of extremely small dimensions it may be very quickly removed from the press and kept in a vault or other place of safety when not in operation. 75

What I claim as my invention is:—

1. In a dome fastener machine, a plurality of dies arranged in succession and adapted to draw the metal into a teat formation, and a spinning die adapted to constrict the metal of the teat to form a neck. 80

2. In a dome fastener machine, a plurality of dies arranged to perform a succession of operations to shape a strip of metal, punches coöperating in unison with said dies, means definitely operated through the operation of the punches for lifting the metal strip clear of the dies, and means operated by the operation of the punches for feeding the metal a predetermined distance when in its raised position. 85

3. In a dome fastener machine, the combination with the dies, of a reciprocating ram, punches carried by said ram, a spinning die, and means operated by the movement of said ram for bringing said spinning die into operating contact with the metal to be formed. 90

4. In a dome fastener machine, a plurality of dies, a plurality of punches adapted to effect the drawing of the metal into a teat formation, a spindle constantly rotated, a pair of jaw-shaped dies mounted on said spindle and adapted to be moved into pressure engagement with the walls of said teat to constrict the metal into a neck formation, means for operating said jaw members in coincidence with the downward movement of said punches, and means for withdrawing said jaw members prior to the completion of the action of the punches. 100

5. In a dome fastener machine, a plurality of dies arranged in a stationary die block, a reciprocating ram, punches coöperating with said dies secured in the punch block on said ram, a vertical spindle arranged beneath said die block, jaw members secured to the top of said spindle and adapted to be swung inwardly and outwardly 115 thereon and having inwardly turned flanged portions adapted to engage the side walls of the metal teat formed by the adjacent dies, means for constantly rotating said spindle, a vertically slideable collet encircling said spindle and adapted to move said jaws inwardly, means operated by the downward movement of the ram for operating said collet to close said jaws inwardly, and means for automatically disengaging said collet operating 120 125 130

means from the ram prior to the completion of its downward stroke.

6. In a dome fastener machine, a plurality of dies arranged in the stationary die block, a reciprocating ram, punches coöperating with said dies secured in the punch block on said ram, a vertical spindle arranged beneath said die block, jaw members secured to the top of said spindle and adapted to be swung inwardly and outwardly thereon and having inwardly turned flanged portions adapted to engage the side walls of the metal teat formed by the adjacent dies, means for constantly rotating said spindle, a vertically slideable collet encircling said spindle and adapted to move said jaws inwardly, a lever mounted on a fixed pivot and having one end operatively connected with said collet, a vertically reciprocating member operatively connected with said lever, a pivotal bar secured to the upper end of said reciprocating member, a pin secured in the ram and operatively engaging said bar in its downward stroke, and means for swinging said pivotal bar out of engagement with said pin intermediate of the stroke of the ram.

7. In a dome fastener machine, a plurality of dies arranged in the stationary die block, a reciprocating ram, punches coöperating with said dies secured in the punch block on said ram, a vertical spindle arranged beneath said die block, jaw members secured to the top of said spindle and adapted to be swung inwardly and outwardly thereon and having inwardly turned flanged portions adapted to engage the side walls of the metal teat formed by the adjacent dies, means for constantly rotating said spindle, a vertically slideable collet encircling said spindle and adapted to move said jaws inwardly, a lever mounted on a fixed pivot and having one end operatively connected with said collet, a horizontally slideable member engaging the free end of said lever and swinging on its pivot to raise the collet, a vertically reciprocating member having a beveled end engaging said horizontally slideable member, a pivotal arm mounted on the upper end of said reciprocating member, a pin secured in the ram and engaging said pivotal arm, and means adapted to swing said pivotal arm to disengage from said pin intermediate of the stroke of the ram.

8. In a dome fastener machine, a plurality of dies arranged in the stationary die block, a reciprocating ram, punches coöperating with said dies secured in the punch block on said ram, a vertical spindle arranged beneath said die block, jaw members secured to the top of said spindle and adapted to be swung inwardly and outwardly thereon and having inwardly turned flanged portions adapted to engage the side walls of

the metal teat formed by the adjacent dies, means for constantly rotating said spindle, a vertically slideable collet encircling said spindle and adapted to move said jaws inwardly, a lever mounted on a fixed pivot and having one end operatively connected with said collet, a vertical reciprocating member adapted to operate said lever to raise said collet, an arm pivotally mounted on the upper end of said reciprocating member, a pin secured in the ram and engaging the upper end of said arm, a cam projection on said arm, and an adjustable obstructing member adapted to engage said cam to swing it on its pivot to disengage from said pin intermediate of the stroke of the ram.

9. In a dome fastener machine, a plurality of dies arranged in the stationary die block, a reciprocating ram, punches coöperating with said dies secured in the punch block on said ram, a vertical spindle arranged beneath said die block, jaw members secured to the top of said spindle and adapted to be swung inwardly and outwardly thereon and having inwardly turned flanged portions adapted to engage the side walls of the metal teat formed by the adjacent dies, means for constantly rotating said spindle, a vertically slideable collet encircling said spindle and adapted to move said jaws inwardly, a lever mounted on a fixed pivot and having one end operatively connected with said collet, a vertically-reciprocating member adapted to operate said lever to raise said collet, an arm pivotally mounted on the upper end of said reciprocating member and adapted to swing laterally in one direction, a spring holding said arm in its vertical position, a cam projection on the side of said arm adjacent to the spring, an adjustable bracket adapted to engage the cam on said pivotal arm to draw it out of engagement with the pin on the ram intermediate of the stroke of the ram.

10. A dome fastener machine, comprising a punch press, a spindle vertically mounted beneath the base of the press, means for rotating said spindle, a sub-press having a ram operatively connected with the ram of the main press, dies in the sub press for shaping the fastener, a spinning die operatively connected with said vertical spindle and adapted to form the neck of the fastener, means for controlling the rotation of the spindle and spinning die, and means connected with said controlling means for locking the main press when the vertical spindle is out of operation.

11. In a dome fastener machine, the combination with a punch press, of a vertical spindle rotatably mounted beneath the body of the press, a vertical flexible shaft operatively connected with said spindle, a friction wheel mounted on the upper end of said flexible shaft and adapted to frictionally en-

- gage the drive wheel of the press, means for holding said friction wheel in contact with the press wheel, means for holding said friction wheel out of engagement with said 5 press wheel, a sub press mounted on the table of the punch press having a plurality of dies and punches, a spinning die for forming the neck of the fastener, means connecting the vertical spindle mounted on the 10 press with said spinning die, and means for locking the control mechanism of the press when the spinning mechanism is disengaged from the press pulley.
12. In a dome fastener machine, the combination with a punch press, of a vertical spindle rotatably mounted beneath the body of the press, a vertical flexible shaft operatively connected with said spindle, a friction wheel mounted on the upper end of said 15 flexible shaft and adapted to frictionally engage the drive wheel of the press, a bar slidably supported on the press, and pivotally connected to the upper end of said flexible shaft, a spiral spring having one end fixed to the press and the other end to the 20 slidably member, means for locking said slidably bar in a position holding the friction wheel out of operating contact, a clutch mechanism for controlling the punch press, 25 an arm secured to said slidably bar and engaging said clutch mechanism to prevent its operation when the friction wheel is out of contact with the press wheel, a sub-press mounted on said punch press and operated thereby, and a spinning die secured to said 30 vertical spindle and adapted to form the neck of the fastener.
13. A dome fastener machine, comprising a punch press having a reciprocating ram, 35 a die block and dies mounted therein, a punch block secured to the ram having punches secured therein coöperating with said dies, a plate extending over said dies and having a longitudinal recess through 40 which the metal strip passes, spring means holding said plate down upon said die block, and means operatively connected with said ram for lifting said plate in the receding motion of the ram.
- 50 14. A dome fastener machine, comprising, a punch press having a reciprocating ram, a die block and dies mounted therein, a punch block secured to the ram having punches secured therein coöperating with 55 said dies, a plate extending over said dies and having a longitudinal recess through which the metal strip passes, spring means holding said plate down upon said die block, an arm pivotally supported from the die 60 block and connected with said plate, a cam mounted on the pivot of said arm, and a pin projecting from the punch block and engaging said cam and adapted to tilt said cam independent of the arm in the downward movement of the punch block and to

tilt said cam and effect the swinging of the arm upon its pivot to lift the plate connected thereto on the upward movement of the ram.

15. A dome fastener machine, comprising, 70 a punch press having a reciprocating ram, a die block and dies mounted therein, a punch block secured to the ram having punches secured therein coöperating with said dies, a plate extending over said dies and having 75 a longitudinal recess through which the metal strip passes, spring means holding said plate down upon said die block, a pair of arms pivotally connected at their inner ends to said plate and pivotally mounted intermediate of their length upon fixed pivots, cam plates mounted on the fixed pivots of said arms having portions extending over said arms and adapted to swing freely inwardly and upon being swung outwardly to 80 tilt said arms on their pivots to lift the plate and pins projecting from the punch block extending into the cam grooves in said cams and adapted to swing said cams outwardly to tilt the arms upon the upward movement 85 of the ram.

16. A dome fastener machine, comprising a press, a die block mounted on the base of said press, dies mounted in said block, a plate resting on said die block and having 90 a longitudinal recess adapted to receive the metal strip from which the fasteners are made and having inwardly projecting stripper plates on the bottom, a plurality of pivotal arms mounted on fixed pivots 95 engaging one side of said plate and spring held thereto, floating blocks slidably arranged in said plate and operatively connected with the inner ends of said levers, counterbalancing levers supported on fixed 100 pivots and engaging said plate at the opposite side thereof from the point of contact of the aforesaid pivotal levers and counterbalancing the spring pressure thereon, a ram, punches secured to said ram, 105 and means operatively connected with said ram for lifting said plate and the floating blocks coincident with the upward movement of the ram.

17. A dome fastener machine, comprising, 110 a press having a die block supported in the base and a ram carrying coöperating punches, a guide plate extending over said punches adapted to receive a strip of metal, means for lifting said guide plate coincident 115 with the raising motion of the ram, and means for feeding the metal strip a predetermined distance coincident with the raising motion of the ram.

18. A dome fastener machine, comprising, 120 a press having a die block supported in the base and a ram carrying coöperating punches, a guide plate extending over said punches adapted to receive a strip of metal, means for lifting said guide plate coincident 125 with the raising motion of the ram, and means for feeding the metal strip a predetermined distance coincident with the raising motion of the ram.

dent with the raising motion of the ram, a pair of feed rolls mounted adjacent to the die block, an arm pivotally mounted intermediate of its length having one end operatively connected to rotate said feed rolls, the other end being engaged by the upward moving ram to operate said feed rolls.

19. A dome fastener machine, comprising, a press having a die block supported in the base and a ram carrying coöperating punches, a guide plate extending over said punches adapted to receive a strip of metal, means for lifting said guide plate coincident with the raising motion of the ram, means for feeding the metal strip a predetermined distance coincident with the raising motion of the ram, and means for regulating the movement of said pivotal arm.

20. A dome fastener machine, comprising, a press having a die block supported in the base and a ram carrying coöperating punches, a guide plate extending over said punches adapted to receive a strip of metal, means for lifting said guide plate coincident with the raising motion of the ram, a pair of feed rolls mounted adjacent to the die block, a clutch mounted on the spindle of one of said feed rolls, a lever pivotally mounted intermediate of its length and having one end adapted to be engaged in the upward movement of the ram to swing it on its pivot, an arm connected to the other end of said lever and operatively connected to said clutch to rotate the same and to effect the rotation of the feed rolls, and means for preventing the backward rotation of the feed rolls.

21. A dome fastener machine, comprising, a press having a die block supported in the base and a ram carrying coöperating punches, a guide plate extending over said punches adapted to receive a strip of metal, means for lifting said guide plate coincident with the raising motion of the ram, a frame secured to the base of the press, a roller mounted in fixed bearings in said frame, a roller mounted in vertically slidable bearings above the aforesaid roller, a clutch casing fixed to one of the slidable bearings of the upper feed roll, a clutch disk fixed to the spindle of the upper feed roll, a second clutch disk mounted on the spindle of the upper feed roll, a clutch casing rotatably mounted on said spindle and encircling the second clutch disk, roller clutch members arranged between said disks and their inclosing casings, a lever pivotally mounted on said frame intermediate of its length, an arm connecting the rotatable clutch casing to one end of said lever, a pin mounted on the ram of said press and engaging the other end of said lever in its upward movement, a spring for retracting said lever on the downward movement of the ram, and an adjustable stop for limiting the

downward movement of the end of the lever engaging the pin on the ram.

22. A dome fastener machine, comprising, a press having a die block supported in the base and a ram carrying coöperating punches, a guide plate extending over said punches adapted to receive a strip of metal, means for lifting said guide plate coincident with the raising motion of the ram, a frame secured to the base of the press, a roller mounted in fixed bearings in said frame, bearing blocks vertically slidable in said frame, a roller mounted in said slidable block, adjustable spring pressure means for holding said rollers in contact, means operating through the upward movement of the ram for rotating the upward roller, and means for regulating the throw of said operating means.

23. In a dome fastener machine, the combination with a punch press, of a feed mechanism comprising a pair of rollers having transversely curved matching surfaces, means for holding said rollers in pressure contact, means for rotating said rollers coincident with the upward movement of the press ram, and means for regulating the movement of said rotative means.

24. In a dome fastener machine in combination a reciprocating press, a plurality of dies arranged on the bed of the said press and adapted to draw the metal in a succession of operations, means for holding the metal strip in contact with said dies, means for definitely lifting the metal clear of said dies operating in synchronism with the raising of the punches, and means for feeding the metal strip in synchronism with said lifting means.

25. In a dome fastener machine, a plurality of dies arranged in succession, a plurality of punches adapted to draw the metal into a teat formation, a spinning die adapted to constrict the metal of the teat to form a neck, a floating punch operating independently of the main punches adapted to hold the metal to the spinning die, and means for operating said floating punch independent of the main punches.

26. In a dome fastener machine, a plurality of dies arranged in succession, a plurality of punches adapted to draw the metal into a teat formation, a spinning die adapted to constrict the metal of the teat to form a neck, a floating punch operating independently of the main punches adapted to hold the metal to the spinning die, a lever supported upon a fixed pivot and operatively connected with said floating die, and means adapted to engage said lever intermediate between its pivot and its point of contact with the floating punch to swing said lever upwardly on its pivot to raise the punch.

27. In a dome fastener machine, a plu-

rality of dies and punches arranged to draw the metal in a succession of operations into a teat formation, a holder for holding the metal strip over said dies, means operated upon the raising of the punch for lifting the holder to clear the metal from the dies, a floating punch supported in said holder, a lever mounted on a fixed pivot and spring

operated to hold said floating punch in contact with the metal being formed, and means 10 operated through the lifting of the holder for engaging said lever and causing it to lift the floating punch with an accelerated movement.
